PHILIP J. LAMOUREUX, OF CAMPAS, WASHINGTON.

DRIER-ROLLS OF PAPER-MAKING MACHINES.

1,139,777.

Specification of Letters Patent.

Patented May 18, 1915.

Application filed August 20, 1914. Serial No. 857,753.

To all whom it may concern:

Be it known that I, PHILIP J. LAMOUREUX, a citizen of the United States, and a resident of Camas, Clarke county, State of Washington, have invented a certain new and useful Improvement in Drier-Rolls of Paper-Making Machines, of which the following is a specification.

My invention relates to the drier rolls of paper making machinery, and particularly to the endless carriers frequently provided in such machines for conducting the leading end of the paper web between the felts of the drier rolls. It is required that the carriers 10 of the leading end of the paper web feed such end forward relatively to the speed of the periphery of said drier rolls, for otherwise there would be a tendency for the paper web to be torn. Since the conducting of the 15 paper web between the felts is only required when starting the web, and when the paper has been accidentally torn, and since the carriers are of considerable length, their constant running imposes upon them undue 20 wear, and causes an unnecessary expense of operation.

Therefore the object of this invention is to provide means for supporting the endless carriers adjacent the periphery of the drier 25 rolls, and rotatable on the axis of the latter, but independently thereof, and means for driving said supporting means at a speed relatively to that of the periphery of the drier rolls, and to so arrange the driving 30 means that they may be thrown into action as required, thus permitting the endless carriers to remain at rest when their service is not required, and in so doing saving them from undue wear.

Another result attained by this invention 35 is that by means thereof the speed of the endless carriers may be controlled and their rotation stopped at will, which gives the operator a better control in the operation of feeding the leading end of the paper web 40 between the drier rolls. Another purpose of this invention is, the means provided for accomplishing the results mentioned are so arranged that they may be applied to the 45 standard forms of paper making machines.

The means by which I attain the results 50 mentioned are hereinafter fully described and illustrated in the accompanying drawings, in which:

Figure 1 is a diagrammatic side elevation of the drier rolls of the paper machine; and

for the purposes of clearness the felts are omitted; Fig. 2 is an elevation of one end of a drier roll showing in half section the journal box in which the latter is mounted, the 60 pulley bearing which is clamped on said journal box, and the pulley which is rotatable on such bearing and which carries the endless carriers; this view being taken approximately on the line 2-2 of Fig. 3; Fig. 65 3 is an end elevation of the parts shown in Fig. 2; and Fig. 4 is a diagrammatic plan view of a portion of the drier roll section, showing a convenient means for driving, at 70 variable speed, the pulleys which support the endless carriers.

The drier rolls are represented by *a*, *b* represents the supporting frame, and *c* the boxes in which the drier rolls are journaled. On the journal box, *c*, at one side of each drier 75 roll, is clamped a fixed bearing *d*, on which is rotatably mounted a pulley *e*. The periphery *f* of such pulley is located adjacent the periphery of the drier rolls, and it is adapted for carrying the two endless carriers *g*. The latter run the full length of the drier roll section, on the pulleys *e*, and are returned to the forward end of said section over the idler pulleys *h*. Weighted 80 idler pulleys, *i*, maintain said endless carriers under uniform tension.

The drier rolls, *a*, are geared together by the gears *m*, so as to cause the rolls to be driven at the same speed and in the proper directions as usual. The prime mover, not 90 shown, imparts the drive to a cone pulley *n*, fixed on a shaft *n'*. A bevel-gear connection *n''* transmits the drive to a shaft *n''*, on which is fixed a spur gear *o*, the latter meshing with and driving two of the drier roll gears 95 *m*. A clutch *s* controls the transmission of power to the drier section.

The endless carriers *g* must be driven approximately at the same speed as the periphery of the drier rolls, in order to carry 100 the leading end of the paper web forward at a speed relative to the speed of rotation of the drier rolls. In order to accomplish such driving, I find it convenient to use the means diagrammatically illustrated in Fig. 4 and 105 110 arranged as follows: Fixed on the shaft *n''* is a cone pulley *p*. Located above the drier roll section is a shaft *t*, also carrying a fixed cone pulley *q*. A belt drive *r* connects the pulleys *p* and *q*. On one end of the shaft *t* 115 is a fixed pulley *u* over which runs the return portion of one of the endless carriers *g*.

For the purpose of providing a good driving contact, the carrier g is wrapped around the pulley u , as shown in Fig. 4. A clutch v permits the pulley u to be thrown into and out of the driving state as desired. When the clutch v is in engagement, the pulley u will be rotated, consequently driving said endless carrier g . The driving of such carrier will then cause the companion carrier g to be driven also at the same speed; the pulleys, e , upon which the carriers g bear being free to rotate on their fixed bearings d . The cone pulleys p and q permit the pulley u to be driven at varying speeds.

15 Claims:

1. In a machine of the character described, the combination with the drier rolls, of rotatable means for supporting endless carriers adjacent the periphery of the drier 20 rolls, such means rotating on the axis of the latter but independently thereof, and means for independently driving said supporting means relatively to the speed of the periphery of said drier rolls.
2. In a machine of the character described, the combination with the drier rolls, of rotatable means for supporting endless carriers adjacent the periphery of the drier 25 rolls, such means rotating on the axis of the latter but independently thereof, driving

means, for said carriers, such means adapted to be connected with and disconnected from the driving means of the drier rolls, means included in said carrier driving means for disconnecting the same from the 35 driving means of the drier rolls, and means for varying the speed of the driving means of the carrier.

3. In a machine of the character described, the combination with the drier rolls and the 40 fixed bearings in which the same are journaled, of pulleys mounted on said fixed bearings and rotating about the axis of the drier rolls, and means for independently driving said pulleys relatively to the speed 45 of the periphery of said drier rolls.

4. In a machine of the character described, the combination with the drier rolls and the 50 fixed bearings in which the same are journaled, of pulleys mounted on said fixed bearings and rotating about the axis of the drier rolls, driving means, for said carriers, such means adapted to be connected with and disconnected from the driving means of the drier rolls, and means for varying the speed 55 of the driving means of the carrier.

PHILIP J. LAMOUREUX.
